UNITED STATES PATENT OFFICE.

JOHN S. ZANT, OF ASPERMONT, TEXAS.

SULKY-PLOW.

No. 805,333.

Specification of Letters Patent.

Patented Nov. 21, 1905.

Application filed June 15, 1905. Serial No. 265,358.

To all whom it may concern:

Be it known that I, JOHN S. ZANT, a citizen of the United States, residing at Aspermont, in the county of Stonewall and State of Texas, have invented certain new and useful Improvements in Sulky-Plows; and I do declare the following to be a full, clear, and exact description of the invention, such as will enable others skilled in the art to which it appertains to make and use the same.

My invention relates to improvements in disk sulky-plows, and more particularly to means for mounting and adjusting the follower or rear furrow wheel.

15 The object of the invention is to provide a simple, durable, and highly efficient means for angularly adjusting the rear caster or follower wheel, which runs in the newly-made furrow, so as to prevent the same from leaving the furrow and to cause the plow to cut uniformly in both hard and soft land.

With the above and other objects in view the invention consists of certain novel features of construction, combination, and arrangement 25 of parts, as will be hereinafter described and claimed.

In the accompanying drawings, Figure 1 is a side elevation of a well-known form of sulky-plow with my improvements applied thereto. Fig. 2 is a top plan view of the same. Fig. 3 is a rear end elevation, and Fig. 4 is a detail vertical sectional view showing the adjusting-levers for the furrow-wheels.

Referring to the drawings by numeral, 1 35 denotes a well-known form of disk sulky-plow, which comprises a beam 2, a carrying-frame 3, and a plow-disk 4. The frame is mounted upon the usual land-wheel 5 and the furrow-wheel 6, which latter is vertically adjustable by means of a hand-lever 7 and angularly adjustable by means of a hand-lever 8. The lever 8 is pivoted by a pin 9 upon one side of a double segmental rack 10, which is mounted upon a frame 18, secured to the 40 rear portion of the beam. Said frame has a rearwardly-extending arm 118, the rear end of which is bifurcated, as at 19. The rear follower-wheel 15 is journaled on a spindle 16 at the lower end of a vertically-disposed shaft 45 17, which is journaled in bearings in the bifurcated portions 19 of arm 118, and on the said shaft is adjustably secured a collar 20, which lies between the parts 19 and holds the said shaft against vertical movement. The 50 lever 8 has a locking-dog 11 to coact with the rack 10 and is connected by a link 12 to a

crank-arm 13 upon the vertical portion 14 of the axle or spindle of the wheel 6. Secured upon the upper end of the shaft 17 is a crank-arm 21, which is adapted to be connected by 60 a link 22 to the lower end of an operating-lever 23. The latter is pivoted by the pin 9 upon the side of the segmental rack 10 opposite to that upon which the lever 8 is pivoted, as clearly shown in Figs. 3 and 4 of the drawings. This lever carries a locking-dog 24 to coact with the rack 10 to hold said lever, and hence the shaft 17 and its wheel 15, in an adjusted position.

It will be seen that when the lever 23 is 70 moved forwardly or rearwardly the angular disposition of the wheel 15 will be changed to cause the plow to cut more or less, as desired. Without this adjustment of the wheel 15 the plow will cut more in hard land and 75 less in soft land, and very frequently this wheel is thrown entirely out of the furrow, whereupon the plow fails to cut at all. By adjusting this rear wheel the same will be caused to remain in the furrow and the plow 80 can be made to cut uniformly in all kinds of earth.

From the foregoing description, taken in connection with the accompanying drawings, the construction and operation of the invention 85 will be readily understood without requiring a more extended explanation.

Having thus described my invention, what I claim as new, and desire to secure by Letters Patent, is—

1. A sulky-plow, having a beam, a front frame and a rear frame, land and furrow wheels on opposite sides of the front frame, a vertical shaft mounted in the front frame for angular movement, and having a spindle for 95 the furrow-wheel and also provided with a crank, a disk carried by the beam, a follower-wheel in rear of the disk, a vertical shaft mounted in the rear frame for angular movement and having a spindle for the follower-wheel, and also provided with a crank, a segment-rack on the rear frame, levers on opposite sides of said segment-rack, each having a dog to engage the rack, and links connecting the respective levers to the respective cranks 100 of the furrow and follower wheel vertical shafts.

2. A sulky-plow having a beam, a front frame and a rear frame, each attached to the beam, said rear frame having a rearwardly-extending arm and an upwardly-extending segment-rack, land and furrow wheels on op-

posite sides of the front frame, a vertical shaft mounted in the front frame for angular movement and provided with a crank at its upper end and with a spindle at its lower end
5 for the furrow-wheel, a disk carried by the beam, a follower-wheel in rear of the disk, a vertical shaft having its bearings in the arm of the rear frame and provided at its upper end with a crank and at its lower end with a
10 spindle for the follower-wheel, levers on opposite sides of the segment-rack, each having

a dog to engage the rack, and links connecting the respective levers to the respective cranks of the furrow and follower wheel vertical shafts.

15

In testimony whereof I have hereunto set my hand in presence of two subscribing witnesses.

JOHN S. ZANT.
